UNITED STATES PATENT OFFICE.

HERMAN A. GROTH, OF OAK PARK, ILLINOIS, ASSIGNOR TO WM. H. RANKIN COMPANY, OF CHICAGO, ILLINOIS.

DESIGN FOR A BOTTLE OR SIMILAR CONTAINER.

Application filed November 14, 1928. Serial No. 28,980. Term of patent 14 years.

To all whom it may concern:

Be it known that I, HERMAN A. GROTH, a citizen of the United States, residing at Oak Park, Illinois, have invented a new, original, and ornamental Design for a Bottle or Similar Container, of which the following is a specification, reference being had to the accompanying drawing, forming part thereof.

The figure is a perspective view of a bottle embodying my design.

I claim:

The ornamental design for a bottle or similar container, as shown.

HERMAN A. GROTH.
